UNITED STATES PATENT OFFICE.

ROBERT HUNTER, OF SPOKANE, WASHINGTON.

CONCENTRATING-TABLE.

1,151,466.

Specification of Letters Patent. Patented Aug. 24, 1915.

Application filed May 5, 1914. Serial No. 836,524.

To all whom it may concern:

Be it known that I, ROBERT HUNTER, a citizen of the United States, residing at Spokane, in the county of Spokane and 5 State of Washington, have invented new and useful Improvements in Concentrating-Tables, of which the following is a specification.

This invention is an improved ore concentrating table, the object of the invention being to provide an improved machine of this kind in which the table, when in operation, is given reciprocating movement both longitudinally and transversely there- 10 by greatly facilitating the concentration of the ore particles in the pockets between the riffles and also facilitating the separation and discharge of the worthless particles.

One object of the invention is to effect 20 improvements in the construction of the concentrating table.

Another object is to provide improved means for reciprocating the concentrating table both longitudinally and transversely.

25 The invention consists in the construction, combination and arrangement of devices hereinafter described and claimed.

In the accompanying drawings: Figure 1 is a plan of an ore concentrating table 30 constructed in accordance with my invention. Fig. 2 is a vertical longitudinal sectional view of the same. Fig. 3 is a plan of the same with the table removed so as to disclose the construction of the shaking carriages and their operating mechanism. Fig. 25 4 is a vertical transverse sectional view of the same on the plane indicated by the line *a—a* of Fig. 2. Fig. 5 is a similar view on the plane indicated by the line *b—b* of 40 Fig. 2.

The base frame 1 of my improved ore concentrating table is of oblong rectangular form comprising longitudinal side members 2 and transverse end members 3 on the upper 45 sides of the side members and a pair of cross bars 4 one of which is near one end of the frame the other cross bar being at a suitable distance from the opposite end of the frame. The length of these cross bars exceeds the 50 width of the frame and the ends of the cross bars project beyond opposite sides of the frame and are provided on their upper sides with supporting guides 5. Each of said guides has a V-shaped groove 6 in its 55 upper side, the said groove being arranged transversely with respect to the base frame.

A lower carriage 7 is provided which is here shown as comprising a pair of transversely arranged end bars 8 and a longitudinal bar 9 which connects said end bars. At 60 the ends of the end bars are slides 10 each of which is provided on its lower side with an oppositely beveled guide tongue 11 which operates in one of the guide grooves 6 so that the lower carriage is mounted on the 65 base frame having reciprocating movement transversely of the base frame. Each slide 10 is provided in its upper side with a V-shaped groove 12^a which is arranged transversely of said slide and longitudinally with 70 respect to the base frame. An upper carriage 12 is also provided which as here shown is of oblong rectangular form comprising side bars 13, end bars 14 and an intermediate cross bar 15. The side bars 75 are provided on their lower sides at points near their ends with cross sectionally V-shaped longitudinal slides 16 which are fitted and operate in the guide grooves 12 of the slides 10 so that the upper carriage is 80 mounted on the lower carriage for reciprocating, longitudinal movement, and it will be understood that since the upper carriage 85 is mounted on the lower transversely movable carriage said upper carriage also moves or is adapted to move transversely.

At one end of the base frame 1 is a transversely arranged bed plate 17 which is bolted on the base frame, is provided with a central opening 18 and is also provided 90 on its ends with a pair of bearings 19. A shaft 20 is mounted in the said bearings and is provided near its center with a pair of cam arms 21—22 these cam arms being arranged at about 90° apart, and being of the 95 shape shown in Fig. 2, each being rounded on one side as at 21^a and relatively flattened on the opposite side as at 21^b. A crank wheel 23 is here shown at one end of the said shaft to enable the same to be rotated. 100 Any suitable means may be employed for this purpose.

A pair of yokes 24—25 are respectively operated by the cam arms 21—22, each of said yokes having an opening, here shown as substantially rectangular in form, in which one of said cam arms operates, the said openings being longer in their vertical dimensions than in their transverse dimensions so that the cam arms, while they clear the upper 110 end and lower sides of the yokes will be caused to engage the vertical opposite sides

thereof and hence impart reciprocating motion to said yokes. The yoke 24 has oppositely extended guide and supporting arms 26-27 and the yoke 25 has similar arms 28-29. The arms of the yokes are mounted for reciprocating movement in bearing blocks 30-31 which are mounted on opposite sides of the bed plate 17. The guide arms of the yokes are rectangular in cross section and the openings in the bearings 30-31 engaged by said guide arms are correspondingly shaped so that the yokes while free to reciprocate are prevented from turning.

15 A shaft 32 extends transversely of the base frame at a suitable distance from the bed plate and a pair of rocking arms 33-34 are mounted on said shaft. The rocking arm 33 is connected to the arm 27 of the yoke 24 by a link 35 and the rocking arm 34 is connected to the arm 29 of the yoke 25 by a similar link 36. Hence the rocking arms are actuated by the yokes and the cam arms as will be understood.

20 A bell crank 37 is mounted on a supporting block 38 on one side of the base frame, for pivotal or angular movement in a horizontal plane and one arm of the bell crank is pivotally connected as at 39 to the bar 9 of the lower carriage. The other arm of the bell crank is pivotally connected as at 40 to one end of a pitman 41, the opposite end of the pitman being pivotally connected as at 42 to a sleeve link 43 which is adjustably mounted on the rock arm 33 and may be secured to said rock arm at any desired adjustment by means of a set screw 44. A similar sleeve link 45 is adjustably secured by a set screw 46 on the rock arm 34. A pitman 47 has one end pivotally connected to the sleeve link 45 as at 48 and the other end pivotally connected as at 49 to the cross bar 15 of the upper carriage 12. It will be understood from the foregoing that the rock arms and their connections and actuating elements cause the lower carriage to reciprocate transversely and the upper carriage, which is carried by and hence moved transversely with the lower carriage is caused to also reciprocate longitudinally.

50 The table 50 is provided near its ends, on its under side, with bolsters 51 which are provided near their ends with feet 52^a that bear on opposite sides of the upper carriage 12 and are provided at their centers with securing studs 53 which engage openings in the centers of the end bars 14 of said upper carriage and thereby the table is detachably mounted on the upper carriage and when engaged therewith is adapted to be reciprocated both longitudinally and transversely with the upper carriage.

55 The table top comprises a main or longitudinal plane 52 which opens at one end of 60 the table as at 53 and a transverse plane 54

which is at the opposite end of the table and inclined transversely thereto and extends down to the adjacent portion of the longitudinal plane 52. The latter plane also inclines laterally toward the corner 55. The transversely inclined plane 54 is provided around three of its sides with walls 56-57-58, the latter being also common to and forming a side wall of the main plane 52 and at the lower side of said main plane. 75 A wall 59 is also provided for the transverse inclined plane 54 the said wall rising from and extending about half way across the main plane 52 and reaching from the higher end of the plane 54 nearly to the lower end thereof. The plane 54 is provided with riffles 60 which serve to spread or distribute the pulp. These riffles are arranged at an angle to one another and form between them a series of pockets 61, the arrangement of the pockets and riffles being approximately radial and the said riffles extending nearly but not entirely across the plane 54, the pockets widening outwardly toward their discharge ends and the lowermost riffles 90 and pockets extending also partly across the main plane 52. On the said plane 52 are a series of longitudinally arranged riffles 62 which are at right angles to the lowermost riffle 60 and extend therefrom, the said riffles 62 being of unequal length, the shortest being near the inner end of the walls 59. Pockets 63 are formed between the progressively lengthened riffles 62. That portion of the main plane 52 which is divided from the plane 54 by the wall 59 is also provided with a series of riffles 64 of unequal lengths, which lengthen progressively as they approach the side of the said plane opposite the wall 58, pockets 65 being formed between 100 the riffles 64.

105 In the operation of the machine, while the table is being reciprocated longitudinally and transversely, the material to be concentrated is supplied to the table at the upper end of the transversely inclined plane 54. The double reciprocating and jarring movements of the table cause the heavier metal bearing ore particles to settle in the pockets, such particles as are swept over one 115 riffle being caught in a pocket below. The mass of material is spread or distributed on and passes spirally or in a curved line from the inclined plane 54 down upon the main plane 52 where concentration is effected the 120 lighter worthless particles passing outwardly beyond the outer ends of the pockets and the heavier metal bearing particles being caught in the pockets between the riffles, the worthless particles being finally 125 discharged over the open end 53 of the table. When the shaft 20 is turned in the direction indicated by the arrow in Fig. 2, the evolute rounded edges 21^a of the cam arms act progressively and continuously in 130

imparting comparatively easy longitudinal movements to the yokes so that easy sliding movements, longitudinal and transverse, are imparted to the concentrating table. When 5 the shaft 20 is turned in the reverse direction, the flattened sides or edges 21^b of the cam arms intermittently engage the yokes so that jarring movements are imparted to the latter, and hence jarring longitudinal and 10 transverse reciprocating motions are communicated to the table. The riffles 60 on the transversely inclined plane 54 are triangular in form transversely so that each of them is provided with an inclined upper side 66 to 15 facilitate the movement of material thereover. Each of the riffles 62—64 of the main plane 52 is rectangular in form transversely and has a longitudinally inclined upper surface 67, said riffles being highest at the end 20 next the inclined plane 54 and lowest near the discharge end 53 of the table.

Having thus described my invention, I claim:—

1. In an ore concentrating machine a table having a longitudinal main plane and a transversely inclined plane at one end of and arranged to discharge on to the main plane, said transversely inclined plane having a series of substantially radial riffles and 25 pockets, the latter broadening toward their outer ends and said riffles and pockets extending partially across said inclined plane and the lowermost of said riffles and pockets also extending partially across the main 30 plane and longitudinally arranged series of riffles and pockets on said main plane.
2. In an ore concentrating machine a table having a longitudinal main plane and a transversely inclined plane at one end of 35 and arranged to discharge on to the main plane, said transversely inclined plane having a series of substantially radial riffles and pockets, the latter broadening toward their outer ends and said riffles and pockets ex- 40 tending partially across said inclined plane 45

and the lowermost of said riffles and pockets also extending partially across the main plane and longitudinally arranged series of riffles and pockets on said main plane, the said substantially radially arranged riffles 50 of the transversely inclined plane having transversely inclined upper surfaces and the longitudinally arranged riffles of the main plane having longitudinally inclined upper surfaces extending downwardly toward the 55 discharge end of said main plane, in combination with means to impart longitudinal and transverse reciprocating motions to said table.

3. In an ore concentrating machine a table 60 mounted for reciprocating longitudinal and transverse movement and comprising a longitudinally arranged main plane and a transversely arranged inclined plane at one end of and extending partly across the main 65 plane, said table having a vertical wall separating the major portion of the transversely inclined plane from the main plane, said transversely inclined plane having substantially radially arranged riffles and pockets 70 closed at the ends next said vertical wall and open at the opposite ends of and some of said riffles and pockets sweeping around the inner end of said wall, and said main plane being provided with a longitudinally 75 arranged series of riffles extending from the lowermost of the first-named riffles and a similar series of riffles extending from said transverse vertical wall, the said riffles of each series on the main plane being progressively lengthened toward the side of said main plane opposite that on which the inclined transversely arranged plane discharges.

In testimony whereof I affix my signature 85 in presence of two witnesses.

ROBERT HUNTER.
